Ottokars

UNITED STATES PATENT OFFICE.

OTTO KRAUS, OF NEW YORK, N. Y.

GARMENT-SUPPORTER.

SPECIFICATION forming part of Letters Patent No. 772,620, dated October 18, 1904.

Application filed March 26, 1904. Serial No. 198,956. (No model.)

To all whom it may concern:

Be it known that I, OTTO KRAUS, a citizen of the United States, and a resident of the borough of Manhattan, in the city of New York, and State of New York, have invented certain new and useful Improvements in Garment-Supporters, of which the following is a specification.

This invention relates to garment-supporters, and has for its more prominent objects high efficiency of service with fabrics of varying thickness and texture, as well as great facility for application to clasp the fabric and convenience for permitting the ready release of the same.

With the above purposes in view the novel garment-supporter comprises a member carrying a stud or projection having a shoulder at one side and a clamping member embodying a loop adapted to embrace said stud or projection and provided with a peculiarly operating pivoted jaw adapted to coact with a part of said loop to clamp the stud or projection at opposite sides of the latter, one of 25 the clamping portions being engaged beneath the shoulder of the stud or projection.

The novel construction is preferably so conditioned that the clamping action aforesaid will be of yielding character, thus adapting 30 the supporter to serve with different thicknesses of fabric. Moreover, the disposition of the jaw when in a clamping position insures a more positive locking action of the clamping member as the tension on the fabric is increased.

There are other important features connected with the invention, which, besides those alluded to, are clearly set forth in the subsequent detailed description.

In the accompanying drawings, forming part of this specification, Figure 1 is a front or face view of the clamping members of a garment-supporter embodying one form of my invention and representing the same in 45 the closed position, the lower portion of the stud-supporting plate being broken away. Fig. 2 is a side view of the device disclosed in Fig. 1 with the webbing attached, the disengaged position of the outer clamping member 50 being indicated in dotted lines. Fig. 3 is a

view somewhat similar to Fig. 1, but showing the device operatively suspended and engaged with a fabric. Fig. 4 is a front or face view illustrating a modified form of the supporter in a closed position. Fig. 5 is a side view of 55 the device disclosed in the preceding figure and indicating by dotted lines the clamping member in a disengaged position. Figs. 6 and 7 are face views of still further forms of the invention. Fig. 7^a is a side edge view of the 60 supporter illustrated in Fig. 7. Fig. 8 is a detail section illustrating a modification of the stud or projection and its supporting-plate. Fig. 9 is a side elevation of the stud and plate viewed from a position at a right 65 angle to that in which such parts appear in the preceding figure. Figs. 10 and 11 are views corresponding in general character with Figs. 8 and 9 and illustrating still another 70 modification of the stud or projection and its supporting-plate.

Similar reference characters are employed to designate corresponding parts in the several figures of the drawings wherein they occur.

As disclosed, the novel garment-supporter embodies two members A and B, the former of which comprises a plate α , having upper and lower slots through which the supporting-webbing C is threaded and terminates in a fold c , stitched to the contiguous part of the webbing in a manner well understood in this class of articles. At a higher point the webbing is folded and stitched to present a bight 75 c' for the suspension of the member B, as will be presently explained.

In Figs. 1 to 3, inclusive, the plate α is shown as centrally carrying a horizontally-extending stud or projection A', which is positively connected to said plate by reason of the enlarged 80 base α' of the stud being clamped at opposite points by ears α^2 , struck up from the body of the plate and bent over into engagement with said base. At its extreme outer portion the stud has a lower transverse shoulder α^3 . This 85 stud is preferably of moderately soft rubber.

The member B includes a lower loop B', intermediately-located shank b , and upper suspending cross-bar b' , all of which are formed by suitably bending a single piece of wire, the 90

terminal portions of which are arranged to present the relatively spread upper part, the top of which is defined by the inwardly-turned horizontal ends of the wire, which are embraced by a thin sheet-metal sleeve b^2 to provide the proper cross-bar aforesaid for bearing in the bight to permit the member B to be moved to and from the member A. The loop B' is of ample capacity indicated for permitting it to take freely over the stud, and with the lower cross-bar b^3 engaged beneath the shoulder a^3 the upper transverse part b^4 of said loop will be some distance from the corresponding side of the projection. The upper transverse part b^4 referred to is formed by the inward horizontal bends of the wire in completing the loop and at the point of emergence of the latter with the shank. Pivotally mounted upon the transverse part b^4 is a clamping-jaw D, which may be sheet metal and which, besides the gripping portion d , embodies the cylindrical part d' for contributing to the pivotal feature and an upper vertically-extended tongue d'' , the latter being of such configuration and so flanged at the sides that it can be moved to lie intimately against the shank and diverging branches immediately at the top of the latter, with the side flanges externally embracing said shank and branches, under which conditions the clamping-jaw will be retained against lateral displacement and a compact arrangement provided admitting of the convenient outward swinging of the tongue on its fulcrum by the mere insertion of the finger-nail or other object beneath the edge d^3 of the upper widened portion of the tongue. Manifestly such outward movement of said tongue will effect the disengagement of the gripping portion of the clamping-jaw from frictional engagement with the upper side of the stud.

From the description thus far it will be readily comprehended that with the members A and B' in a relatively open position the fabric E of the hose or other garment can be adjusted immediately in front of the stud, so that, as thus conditioned, the member B, with its clamping-jaw, as indicated in dotted lines, Fig. 2, can be adjusted so that its loop B' will take over the fabric-covered stud, and so press the fabric that the latter will generally conform to said stud, after which operation the tongue d'' can be moved back upon the shank to cause the gripping portion d to swing to a position slightly forward of the vertical plane in which the lower cross-bar b^3 is located. The forward movement of the gripping portion d referred to will result in its bearing against the upper side of the stud A' and in a manner to draw the lower cross-bar b^3 in engagement beneath the shoulder a^3 of said stud, and thus positively clamp and retain the fabric in engagement with the stud.

As will be noted by reference to Fig. 2, the gripping portion d in its clamping position

bears against the upperside of the stud forward of a plane intersecting the pivot of the clamping-jaw and lower engaged bar of the loop and is stopped against further forward movement by the limiting contact of the tongue with the shank b . Consequently any downward pull of the fabric will tend to still further force the tongue against the shank, and thereby secure a highly-efficient locking effect for the device. The resilient character of the stud as well as the somewhat similar quality of the loop promote the adaptability for clamping different thicknesses of fabric. When the fabric is to be released, the forward swinging of the tongue will rearwardly move the portion d clear of the stud, and the cross-bar b^3 under the tension of the fabric will then be disengaged from the shoulder and the loop withdrawn from its position with respect to the stud.

In Figs. 4 and 5 an embodiment of the invention is illustrated wherein the clamping-jaw D' is of sheet metal and presents in one piece the vertically-extended shank d' , having the upper cylindrical fold d^5 , the intermediate bearing-sleeve d^6 , and lower gripping portion d^7 , said sleeve d^6 and gripping portion d^7 being formed by folding a part of the metal section at the rear of the jaw and turning the end of said section, as well as swelling the contiguous forward part of the jaw, to conjointly constitute the sleeve d^6 aforesaid. A loop B², hung in the bight of the webbing, has its lower bar revolvably embraced by the upper cylindrical fold d^5 of the jaw to pivotally suspend the latter, bends b^3 of the loop at each end of the last-mentioned bar confining the jaw connection against lateral movement. Pivotally bearing in the sleeve d^6 of the jaw is the upper cross-bar b^6 of an approximately rectangular loop B³, of such capacity as to adapt it for freely taking over the stud A², forwardly extending from the other member A³ of the supporter. By slightly swinging upward the loop B³ the jaw D' and the stud A² can assume such positions with respect to each other that the loop B³ can be passed down over the stud, whereby upon bringing the parts to their normal vertical positions the suspending-loop B³ will downwardly move the jaw, so that the gripping portion of the latter will be forced against the upper side of the shank of the stud, such movements coincidently serving to throw the sleeve d^6 toward the member A³ and result in the lower cross-bar of the loop B³ being drawn upwardly to firmly clamp the stud-shank between such cross-bar and the edge of the gripping portion. Therefore, if previous to closing the clamping-jaw and loop B³, as set forth, a fabric is adjusted immediately in front of the stud, the loop B³ taking over said stud will press the fabric upon and around the same, and such fabric will be positively held by the mutual clamping action of the lower cross-

bar of the loop B^3 and gripping portion of the jaw. Lateral projections d^9 on the gripping-jaw D^3 , contacting with the loop when the jaw is in a clamped position, serve as stops to limit the forward movement of said gripping portion. By simply tilting the jaw D^3 the loop B^3 can be withdrawn from the stud to readily release the fabric in a manner clearly apparent. In this construction, as in that previously described, the conditions controlling the locking of the clamping-jaw are the same, the engaging point of the jaw being forward of a plane intersecting its pivot and the lower engaging bar.

5 In Fig. 6 the clamping-jaw D^3 is shown as pivotally mounted on the lower cross-bar of the loop B^3 , so that the gripping portion d^9 of said jaw is adapted to bear against the under side of the shank of the stud and operate 10 to force said shank and clamp the same against the upper transverse part d^{10} of the loop. The gripping portion d^9 has lateral stops d^{11} , performing functions similar to the stops d^8 of the two preceding figures. An integral tongue 15 d^{12} , extending beyond the lower cross-bar of the loop B^3 , provides a convenient means for manipulating the clamping-jaw.

Fig. 7 discloses an arrangement wherein the clamping member is of sheet metal and 20 comprises in a single piece a main part presenting the upper slotted end b^7 for bearing in the webbing-bight and the lower loop b^8 , the metal at the inner edge of which is turned to form a rounded gripping part. The gripping-jaw, 25 which is also of sheet metal, comprises the upper operating-tongue d^{13} and lower gripping portion d^{14} , the pivotal feature of this jaw being provided by intermediately-located 30 side lugs d^{15} , revolubly retained by ears b^9 , struck up from the metal of the main part of the member and bent over to confine the lugs. The metal at the gripping edge of the portion 35 d^{14} is also turned to secure a proper engaging capacity and avoid cutting the shank of the stud. The operation and advantages of this 40 construction will be readily apparent.

In Fig. 7^a the stud A^4 is shown as having 45 similarly-formed shoulders a^4 a^5 both at its top and bottom. The upper portion of the jaw-carrying frame B^6 is forwardly curved, so that its points of suspension will be in a vertical plane coinciding with the points of 50 stud engagement of the gripping portion d^{14} of the pivoted jaw D^3 and the lower cross-bar b^8 of the frame, thus positioning the jaw-pivot at the rear of the stud engagement of the gripping-point, and thus exercising the functions to attain the locking conditions of the previously-described conditions.

The construction and arrangement of the 55 stud may widely vary. For instance, in Figs. 8 and 9 the stud-supporting plate A^5 has a stud-body a^6 , configurated as indicated in Fig. 65 8, the lower ends of said body being in the

form of shoulders, and short tenons a^7 , the latter of which are passed through the offset portions of inner transverse slots, the outer engaging shoulder a^8 of the stud-body a^6 being normally externally undefined by reason 70 of a covering-strip a^9 of yielding material, such as rubber, such strips being secured by having its end portions a^{10} passed down through the main portions of the inner slots before referred to, said end portions being 75 clamped by underturned lips a^{11} , formed by slitting and bending the metal near the outer portions of the plate A^5 , which operation also results in forming the main slots for engaging 80 the suspending webbing with said plate.

In Figs. 10 and 11 the body of the stud is of moderate soft rubber and has a pronounced shoulder a^{12} on one side of its head and a smaller shoulder a^{13} at the opposite side, so that the clamping engagements will be in different planes, respectively, for purposes previously described. The plate A^6 has a centrally-depressed portion a^{14} , which is undercut at opposite sides. The base a^{15} of the stud-body approaches a dovetail shape, so 90 that it can be sprung within the depression. The stud-body has a transverse opening a^{16} , into which from opposite ends thereof spurs a^{17} , integral with the plate A^6 , are bent to securely confine the stud-body in position.

The stud or projection may be wholly or in part of yielding character and be of a material other than rubber, as felt, leather, and the like.

I do not wish to be understood as limiting 100 myself to the precise arrangements and constructions of parts shown and described, but reserve the right to all modifications within the scope of my invention.

Having now described my invention, what 105 I claim as new, and desire to secure by Letters Patent, is—

1. A garment-supporter comprising a member carrying a stud or projection, and a second member embodying a pivoted clamping-jaw and oppositely-located clamping part, such second member being flexibly connected 110 with the first member, said jaw adapted to coact with said part whereby the stud or projection will be clamped between such part and 115 said jaw.

2. A garment-supporter comprising a member carrying a stud or projection, and a second member embodying a pivoted clamping-jaw and oppositely-located clamping part, such second member being flexibly connected 120 with the first member, said jaw adapted to coact with said part, whereby the stud or projection will be clamped between such part and 125 said jaw, both of said members being suspended for free swinging movement.

3. A garment-supporter comprising a member carrying a yielding stud or projection, and a second member embodying a pivoted 130 clamping-jaw and oppositely-located clamping

part, such second member being flexibly connected with the first member, said jaw adapted to coact with said part, whereby the stud or projection will be clamped between such part and said jaw.

4. A garment-supporter comprising a member carrying a stud or projection, having a shoulder, and a second member embodying a pivoted clamping-jaw and oppositely-located clamping part, such second member being flexibly connected with the first member, said jaw adapted to coact with said part, whereby the stud or projection will be clamped between such part and said jaw, the part being engaged beneath the shoulder.

5. A garment-supporter comprising a member carrying a stud or projection, and a second member embodying a pivoted clamping-jaw and oppositely-located clamping part, such second member being flexibly connected with the first member, said jaw adapted when moved to engage the stud at one side and draw the clamping part in engagement with an opposite side of said stud.

25 6. A garment-supporter comprising a member carrying a stud or projection, and a second member embodying a pivoted clamping-jaw and oppositely-located clamping part, such second member being flexibly connected with the first member, said jaw adapted to coact with said part whereby the stud or projection will be clamped between such part and said jaw, together with a stop for limiting the gripping movement of the clamping-jaw.

35 7. A garment-supporter comprising a member carrying a stud or projection, and a second member embodying a wire frame including a clamping part, a sheet-metal clamping-jaw pivotally connected with said frame and movable outward from the first-mentioned member in order to assume a clamping position, said jaw adapted to coact with said clamping part, whereby the shank of said stud or projection will be clamped between such part and said jaw.

45 8. A garment-supporter comprising a member carrying a stud or projection, and a second member embodying a pivoted clamping-jaw and a wire frame, the latter presenting a clamping part located opposite with respect to the gripping portion of said jaw, whereby the stud or projection will be clamped between such part and said jaw, the gripping portion of said jaw when in a clamped position being forward of the jaw-pivot, and the distance of the lower clamping part from said pivot being always the same.

55 9. A garment-supporter comprising a member carrying a stud or projection, and a second member embodying a clamping part and side bars presenting an opening for the reception of said stud or projection with clearances between the stud and side bars, and a clamping-jaw adapted to coact with said clamping part, whereby the stud or projec-

tion will be clamped between such part and said jaw.

10. A garment-supporter comprising a member carrying a stud or projection, and a second member embodying a loop having a pivoted clamping-bar and extended shank, and a pivoted clamping-jaw adapted to coact with said clamping-bar whereby the stud or projection will be clamped between such bar and the jaw, the latter having a tongue which lies closely adjacent to the extended shank when the jaw is in a clamped position.

11. A garment-supporter comprising a member carrying a stud or projection, and a second member embodying a loop having a clamping-bar and extended shank, the latter merging in a spread portion, and a pivoted clamping-jaw adapted to coact with said clamping-bar whereby the stud or projection will be clamped between such bar and the jaw, the latter having a tongue the free extremity of which is contiguous to the spread portion of the shank when the jaw is in a clamped position.

12. A garment-supporter comprising a member carrying a stud or projection, and a second member embodying a loop having a clamping-bar and extended shank, and a pivoted clamping-jaw adapted to coact with said clamping-bar, whereby the stud or projection will be clamped between such bar and the jaw, the latter having an operating-tongue provided with side flanges for externally embracing the loop-shank, when the clamping-jaw is in a gripping position.

13. A garment-supporter comprising a member provided with a plate having ears, a stud or projection having an enlarged base clamped by said ears, and a second member embodying a pivoted clamping-jaw and oppositely-located clamping part, said jaw adapted to coact with said part, whereby the stud or projection will be clamped between such part and said jaw.

14. A garment-supporter comprising a member carrying a stud or projection, and a second member embodying a pivoted clamping-jaw and oppositely-located clamping part, said second member being flexibly connected with the first member, said jaw adapted to coact with said part, whereby the stud or projection will be clamped between such part and said jaw, one of said clamping elements being of resilient character.

15. A garment-supporter comprising a member carrying a stud or projection, and a second member embodying a pivoted clamping-jaw and oppositely-located resilient clamping-bar, such second member being flexibly connected with the first member, said jaw adapted to coact with said bar, whereby the stud or projection will be clamped between such bar and said jaw.

16. A garment-supporter comprising a member carrying a stud or projection, and a

second member embodying a looped frame having a pivot-bar, a sheet-metal clamping-jaw having a part folded to present a rounded gripping portion and a pivoting-sleeve, said 5 jaw adapted to coact with said frame, whereby the stud or projection will be clamped between a part of such frame and the clamping-jaw.

Signed at New York, in the county of New York and State of New York, this 23d day of 10 March, A. D. 1904.
